LIQUID-CIRCULATING SYSTEM

Hubert Scott-Paine and George Sidney Selman,
Hythe, Southampton, England; said Selman
assignor to said Scott-Paine

Application April 13, 1940, Serial No. 329,562
In Great Britain March 11, 1939

9 Claims. (CL 123—174)

This application corresponds to the application of Hubert Scott-Paine and George Sidney Selman, Serial No. 7,946/39, which was filed in Great Britain on March 11, 1939.

This invention concerns improvements in or relating to liquid-circulating systems, embodying a compensating tank of the kind having one or more inlet and outlet pipes for connection with the circulating system and so arranged that the level of liquid in the tank can vary with the fluctuation of the flow of liquid in the system. The present invention is more particularly concerned with a tank of this kind for use in a liquid-circulating system in which liquid from two or more sources or circuits flow into a common part of the circuit, in which case the tank is arranged to receive the liquid from the two or more sources and deliver it into the common part of the circuit.

An object of the invention is to provide an improved construction of tank which reduces any tendency of the liquid to become turbulent or surge. A tank in fulfilling this object is particularly suitable for use in a boat.

According to this invention a compensating tank of the kind referred to for use in liquid circulating systems is characterised in that an inlet pipe enters the tank at a locality above the normal working level of the liquid therein and is provided with vent holes also above the normal working level of the liquid and has its open discharge end situated near an outlet at the bottom of the tank. With this arrangement any bubbles which may have become entrained in the liquid are quickly released upon entry of the liquid into the tank.

In the case where the compensating tank has two inlet pipes the tank is provided with a vertical baffle and the two inlet pipes are arranged to extend into the tank one on either side of the baffle. Preferably, one or more horizontal baffles are also provided in the tank, one of which is situated closely above the discharge ends of the inlet pipes.

Further features of the invention will be evident from the following description of a preferred example of the invention applied to the liquid cooling system of a V-type internal-combustion engine in a high-speed boat, reference being made to the accompanying drawings in which:

Figure 1 is a vertical section through the tank on the line 1—1 of Figure 2;

Figure 2 is a half-side elevation of the tank looking in the direction of the arrow in Figure 1

and a half section on the line 2—2 of Figure 1; Figure 3 is a horizontal section on the line 3—3 of Figure 2.

Figure 4 is an enlarged view of a part of one of the inlet pipes showing the hood associated with the apertures in the pipe.

Figure 5 is a diagrammatic view showing the tank in a cooling system for an internal-combustion engine employed in driving a boat.

As indicated diagrammatically in Figure 5, the engine is provided with two banks of water-jacketed cylinders 1 provided with inlet pipes 2 and outlets pipes 3, respectively. Cooling liquid is drawn by a pump 4 from a cooling device 5 through a pipe 6 and is delivered to the said inlet pipes 2. The outlet pipes 3 deliver the water from the engine cylinder to the top of a compensating device 7 which delivers it to the cooling device 5 through a pipe 8 whence it flows back again to the pump 4. Thus a closed circuit is provided in two parts. As indicated below, the compensating device is so constructed as to prevent surging of the liquid and also to balance the flow of liquid in the two parts of the circuit. Cooling liquid is circulated through the cooling device by pipes 9.

The tank consists of a metal shell the sides of which, over the middle portion 10 of the tank, are straight (see Figure 2) and extend over about one-third of the height of the tank. The top and bottom portions 11 and 12 of the sides converge first in a curve from the middle portion and then in a straight line towards the top and bottom respectively. The front and back walls 13 and 14 of the tank may be made slightly convex outwardly (see Figures 1 and 3). An outlet to the cooler is provided at the bottom of the tank in the form of an open neck 15 secured to the bottom wall 16 of the tank by means of studs 17.

The tank is provided with a vertical baffle 18 extending between the back and front walls 13 and 14 and from a position closely above the outlet at the bottom of the tank to a position near the top of the straight side portions 10. The baffle is in the form of a rectangular partition provided with suitable openings 19, and its longitudinal edges are bent to form flanges 20 (see Figure 3) by which it is riveted to the front and back of the tank.

The vertical baffle thus divides the lower part of the tank into two compartments 21 and 22; two pipes 23, 24 are mounted in the tank, one in each compartment, and each is formed with a horizontal portion 25 (see Figure 1) passing

through the front of the tank at a position near the top edge 26 of the vertical baffle and each pipe is curved so as to extend through the middle section of the tank and down vertically to a position just past the lower ends of the straight sides 10. The end of each pipe is curved at 27 (see Figure 2) about the same centre as the curved portions of the converging sides 12 of the tank so that the open ends of the pipes are facing towards the outlet in the bottom of the tank and the liquid flowing from them is directed towards the outlet opening. Each pipe is secured in position by a stay 28 adjacent its lower end secured to the side of the tank and by a flange brazed to the pipe and riveted to the wall of the tank at the point of entry of the pipe.

The tank is also provided with two horizontal baffles 30 and 31 of which the baffle 30 is positioned closely above the open discharge ends of the pipes 27 and the other of which baffle 31 is adjacent the top of the straight sides 10 of the tank. Each horizontal baffle is in the form of two plates of thin metal of substantially rectangular form arranged in line one on either side of the vertical baffle (see Figure 3). The corners of the partitions are cut-away so as to leave a small opening 32 at each corner, and the sides are bent over to form flanges 33 which are riveted to the walls of the tank and to the centre baffle. Each of the two-part horizontal baffles is provided with four circular openings 34 to allow passage of the liquid, and two of these at the rear of each portion of the baffle are arranged so that the pipes 23 and 24 pass through them. The other two openings are arranged in the front of each baffle, and in order that these holes may be sufficiently large to allow the required passage of liquid, without undue weakening of the baffle, the holes are arranged on a diagonal in each part of the baffle and are provided with annular stiffening flanges 35 which may face in opposite directions. The holes 19 in the upright baffle are arranged in a similar diagonal manner.

Vent holes 36 are formed in the top of each pipe 23 over that portion of the pipe which is substantially horizontal and which is inside the tank, and, in this example, the vent openings are formed with hoods 37 (see Figure 4) in one piece with the pipe and arranged so that the hood openings are transverse to the pipe axis and the hoods are directed in the direction of flow of liquid in the pipe. Any air which may have become entrained in the water entering the tank is released through the vent holes 36 and is thus prevented from entering the main body of water in the tank, thereby preventing surges being set up in the water. Any water escaping with the air passes into the tank.

The tank is closed at its top end by a wall 38 but has a short piece of pipe 39 extending from one side to the other of the tank and provided with a number of holes 40 over that portion of it which is inside the tank. Thus any air which is vented from the inlet pipes can escape through the open end or ends of this vent pipe.

It is important that the level of the water in the tank, during flow of the liquid, should not rise above the level of the vent holes in the pipes, and accordingly, an inclined filler pipe 41 is arranged with the lower edge of its opening at the desired maximum height of the liquid and is provided with a closure cap 40. In the present example, the lower edge is arranged to be below the underside of the horizontally extending parts

of the inlet pipes 23 so that it is impossible to fill the tank by means of this filler pipe to a level higher than that required. Brackets 44 are attached to the sides of the tank and further brackets 45 are attached to the top of the tank for securing it to a support.

A suitable water-gauge 42 is secured to the tank in order to indicate the level of the water in it, and a test cock 43 is provided in the lower part of the tank.

It will be appreciated that, in the construction described above, any air which may be contained in the liquid flowing into the inlet pipes 23 and 24 is discharged through the vent holes 36 and that the construction of tank, which consists of a number of compartments divided by baffles, reduces the surging of liquid in the tank and opposes any tendency towards the turbulent flow of the liquid.

We claim:

1. A compensating device for connection in a liquid circulating system comprising a tank, filling means near the top of the tank preventing the said tank from being filled above a predetermined level, a vertical baffle in said tank, two inlet pipes arranged one on either side of said baffle so as to extend downwardly through said tank from above said level to near the bottom of the tank, which inlet pipes are provided with vent holes in that part thereof above said level, and an outlet pipe communicating with the bottom of the tank.

2. A compensating device for connection in a liquid circulating system comprising a tank, filling means near the top of the tank preventing the said tank from being filled above a predetermined level, an inlet pipe arranged to extend downwardly through said tank from above said level to near the bottom of the tank, which inlet pipe is provided with vent holes in that part thereof above said predetermined level, an outlet pipe communicating with the bottom of the tank, and a number of horizontal baffles within said tank one of which is situated closely above the discharge end of the inlet pipe.

3. A compensating device for connection in a liquid circulating system comprising a tank, filling means near the top of the tank preventing the said tank from being filled above a predetermined level, an inlet pipe arranged to extend downwardly through said tank from above said level to near the bottom of the tank, which inlet pipe is provided with a number of vent holes in that part thereof above said level, each of said vent holes having associated therewith a hood directed in the direction of flow of liquid in the inlet pipe and an outlet pipe communicating with the bottom of the tank.

4. A compensating device for connection in a liquid circulating system comprising a tank, filling means near the top of the tank preventing the said tank from being filled above a predetermined level, an inlet pipe arranged to extend downwardly through said tank from above said level to near the bottom of the tank, which inlet pipe is provided with vent holes in that part thereof above said level, a number of horizontal baffles in said tank, each arranged with its edges connecting with the sides of the tank and each provided with a number of apertures, one of which baffles is situated closely above the discharge end of the inlet pipe, and an outlet pipe communicating with the bottom of the tank.

5. A compensating device for connection in a

liquid circulating system comprising a tank, filling means near the top of the tank preventing the said tank from being filled above a predetermined level, an inlet pipe arranged to extend downwardly through said tank from above said level to near the bottom of the tank, which inlet pipe is provided with vent holes in that part thereof above said level, a number of sheet metal horizontally disposed baffles each arranged with its edges connecting with the sides of the tank and each provided with a number of circular openings surrounded by lips pressed out of the metal, one of which baffles is situated closely above the discharge end of the inlet pipe, and an outlet pipe communicating with the bottom 15 of the tank.

6. A compensating device for connection in a liquid circulating system comprising a tank which is substantially rectangular in horizontal cross-section, filling means near the top of the tank preventing the said tank from being filled above a predetermined level, an inlet pipe arranged to extend downwardly through said tank from above said level to near the bottom of the tank, which inlet pipe is provided with vent holes in that part thereof above said level, a number of rectangular horizontally disposed baffles each arranged with its edges connecting with the sides of the tank and each having its corners cut away to provide apertures, one of which baffles is situated closely above the discharge end of the inlet pipe, and an outlet pipe communicating with the bottom of the tank.

7. A compensating device for connection in a liquid circulating system comprising a closed tank, filling means near the top of the tank preventing the said tank from being filled above a predetermined level, an inlet pipe arranged to extend downwardly through said tank from above said level to near the bottom of the tank, 40

5 which inlet pipe is provided with vent holes in that part thereof above said level, an outlet pipe communicating with the bottom of the tank, and an open ended pipe extending through the tank from one side thereof to the other side above said level and closely adjacent the top of the tank and having openings therein within the tank.

8. A compensating device for connection in a liquid circulating system comprising a tank, filling means near the top of the tank preventing the said tank from being filled above a predetermined level, an outlet pipe communicating with the bottom of the tank, a vertical centrally disposed baffle terminating a short distance above said outlet pipe, and two inlet pipes extending into the tank one on either side of said vertical baffle and arranged to extend from above said level down to near the bottom of the tank, the lower end of each of said inlet pipes being directed towards said outlet pipe and the upper part of each inlet pipe above said level being provided with a number of apertures.

9. A compensating device for connection in a liquid circulating system comprising a tank, filling means near the top of the tank preventing the said tank from being filled above a predetermined level, an inlet pipe arranged to extend horizontally through a side wall of the tank above said level and then to extend downwardly through said tank to near the bottom thereof, which inlet pipe is provided in the horizontal portion thereof within the tank with vent holes each of which vent holes has associated therewith a hood directed in the direction of flow of liquid in the horizontal portion of the inlet pipe, and an outlet pipe communicating with the bottom of the tank.
